UNITED STATES PATENT OFFICE.

BURNET B. LEWIS, OF INDIANAPOLIS, INDIANA, AND LEO M. LEVY, OF NEW YORK, N. Y., ASSIGNEES TO LEWIS NOVELTY MANUFACTURING COMPANY, OF INDIANAPOLIS, INDIANA, A CORPORATION.

POCKET ORNAMENT.

Application filed August 26, 1926. Serial No. 131,666.

This invention pertains to a pocket decoration particularly in the form of a pocket handkerchief usually carried in the breast-pocket of the coat.

5 The object of the invention is to provide a relatively small breast-pocket handkerchief which is removably mounted in an anchoring member adapted to be inserted in the breast-pocket so that the tips of the handkerchief
10 will protrude therefrom. This will give a similar appearance to a full sized handkerchief such as is commonly carried in this manner.

The advantages inherent in the invention
15 reside in the fact that the anchor member is
relatively thin and flat so as to not cause a
bulging of the pocket as is the case with the
ordinary handkerchief. Furthermore it en-
ables one to use an appreciably smaller hand-
kerchief which may be purchased at consid-
20 erably less cost than if it were full sized.

The full nature of the invention will be understood from the accompanying drawings and the following description and 25 claims.

Fig. 1 is a front elevation illustrating the manner of positioning the article in the pocket. Fig. 2 is a front elevation thereof showing the handkerchief mounted in the anchor. Fig. 3 is a plan view of the handkerchief used in this manner.

In the drawings there is shown an individual wearing a coat 10 having a breast-pocket 11 with the tips of the handkerchief 12 protruding therefrom in the usual manner. As illustrated in Figs. 2 and 3, the handkerchief is one of the usual square or rectangular shape, hemstitched about its edges but appreciably smaller in size than the usual handkerchief worn in this manner.

For positioning the handkerchief in the pocket, and holding it in such fashion as to cause the tips thereof to be suitably folded for projecting therefrom, there is provided an anchor member 13 which may be in the form of any thin but stiff material, and preferably made of celluloid. However, it has been made of heavy cardboard. Said anchor

13 may consist of a single flat piece of material such as celluloid or cardboard, or as shown herein, may comprise two separate members adjustable with respect to each other. The member 13^a is shown to be circular in outline and provided with a slotted

strip 13^b through which an elongated strip 55
13^c may extend having a flared bottom 13^d
at one end and the opening 14 at the other
end. This permits the strip 13^c to slide
within the slit portion 13^b for adjusting the
distance of the hole 14 from the bottom of
the anchor. The flared portion 13^b will pre- 60
vent it from being withdrawn upwardly,
while at the same time it is removable from
the other end. This permits the position of
the handkerchief to be adjusted with respect 65
to the depth of the pocket.

In use, the handkerchief is inserted in the opening 14 of the anchor member by passing one corner thereof therethrough and pulling it into position until it is held about its central portion whereby the diagonal corners will be equi-distant in said member. It is then folded upwardly in the manner illustrated in Fig. 2 so that when placed in the pocket it will give the appearance of the usual handkerchief with projecting corners as shown in Fig. 1. This arrangement not only permits of the use of small handkerchiefs or pieces of good material at a much lesser cost than full sized handkerchiefs of the same material, but also economizes in the hemstitching. Furthermore, it permits of various handkerchiefs of this character being used since they are readily removable from the member 13 for washing or changing with respect to color and design. By reason of the nature of the material in passing through the opening 14, it will receive the desired folds which will give it the appearance of the usual handkerchief as contrasted with other devices of this character.

The invention claimed is:

1. In an article of the character described, a rectangular handkerchief and a retaining anchor therefor comprising two members adjustable with respect to each other, one of said members having an opening therein, said members consisting of relatively flat and stiff material, whereby said handkerchief may be inserted in said opening and retained by said anchor in adjusted position with respect to the bottom thereof. 95 100

2. In an article of the character described, the combination with a handkerchief, of an anchor member therefor comprising elongated flat stiff material having an opening adjacent one end thereof, said opening being adapted to removably receive said handker- 105

chief for securing it in position and causing its ends to be folded for display.

3. In an article of the character described, the combination with a handkerchief, of an anchor member therefor comprising a lower flat piece of material having a pair of parallel slots therein, and a member slidable with respect thereto in said slots, said member having an opening at the upper end thereof

for receiving the handkerchief and lateral ¹⁰ extending portions at the bottom thereof for preventing its passage through said slots, whereby the same is adjustable in height with respect to the lower member.

In witness whereof, we have hereunto aff- ¹⁵ fixed our signatures.
